MIT BESCHRÄNKTER HAFTUNG, OF HAMBURG, GERMANY.

GAS-HEATER FOR TAILORS' IRONS AND THE LIKE.

No. 797,481.

Specification of Letters Patent.

Patented Aug. 15, 1905.

Application filed August 1, 1904. Serial No. 219,081.

To all whom it may concern:

Be it known that I, EMIL HUGO HENNIGER, a subject of the German Emperor, and a resident of Frankfort-on-the-Main, Germany, have invented certain new and useful Improvements in Gas-Heaters for Tailors' Irons and the Like, of which the following is a specification.

This invention relates to gas-heating apparatus for tailors' irons and the like, the closed heating-chamber of which is divisible into separate compartments, whereby with proportionate gas consumption the irons may be heated either in succession or simultaneously to the maximum temperature or to temperatures varying considerably from each other.

Of the heating apparatus heretofore devised, which mainly aimed at providing a more or less powerful draft to the heating-gases by employing baffle-plates, channels, chimney connections, and the like in order thereby to obtain combustion smokeless or as economical as possible, none so far as I am aware fulfil the practical requirements arising in the tailoring trade especially in large businesses—namely, to supply the worker at any time, according to the work at which he is employed, with irons ready to hand and at the right temperature. With such heaters as have been previously used the temperature to be realized must be adjusted according to the time or the irons after removal must be correspondingly cooled, whereby time and gas are lost. With the present heating apparatus all variations of temperature of the irons can be provided for according as is desired. The present invention combines with minimum gas consumption all the advantages of a practical gas iron-heater.

In the accompanying drawings, Figure 1 is a central transverse section of a gas iron-heater constructed in accordance with and embodying my invention; Fig. 2, a horizontal section of the heater on the line I I, Fig. 1; Fig. 3, a vertical longitudinal section of the heater on the line II II, Fig. 1; and Fig. 4, a detailed perspective view of a grate or grid.

Similar characters of reference refer to similar parts throughout the several views.

In a frame *b*, provided with suitable feet *a*, which frame has in front a plate *c*, upon which the irons *f* may be rested, are mounted, say,

for instance, three burners *d* *d*² *d*³ and ignition-tubes or pilot flame-burners *e* *e*² *e*³ over air-slots *c*, formed between two deflector-plates *e*. The said air-slots are covered by plates *e* below and spaced from the deflectors *e* in order to insure regular and undisturbed entry of the air to the jets. At the same elevation or height as the said plate *c* there are supported within the frame grates or grids *r*, on which the irons are placed. The grids *r*, surrounding the burners, have preferably the form shown in Fig. 4. Above the frame *b* is the special heating-chamber, which may be closed all round by non-conducting walls *g*. The front wall may be formed as a door *h*, hinged along the top and provided with a handle *h*', Fig. 1, while the rear wall is provided with a pipe *y* for the products of combustion. In order that the hot gases may flow so far as possible all round the irons *f*, it is necessary that the said gases be first caused to pass upward, and for this purpose a partition-plate *i*, provided on the top with transverse orifices *i*', is built into the heater. By this means an obstacle to the motion of the gases is provided, so that the said gases remain longer within the heater and are more perfectly utilized. If desired, guiding plates or baffles can be arranged between the rear wall of the heater and the partition-wall *i*, such baffles being not shown.

The essential feature of the invention consists in dividing or reducing the heating-chamber by the use of movable partition-walls *k*, which consists each of two plates with an interposed non-conducting layer, which partition-walls are guided above in grooved guide-ways *l* and beneath on supporting-rails *m*, supported between the burners or the grids *r* within the frame *b*. By means of this arrangement on the one hand within the same heater irons can be heated to different temperatures, and on the other hand for partial operation to obtain the same working temperature the chamber may be divided into two compartments. Thus a three-chambered heater may by insertion or withdrawal of the partition-walls *k* be so controlled that, first, three burners within three chambers heat three irons, (full operation for maximum temperatures;) secondly, one burner in one chamber heats three irons. Both the partition-walls

are removed, and at each side of the iron f , Fig. 1, is placed another iron f' —that is to say, the three irons set on a single grate, (full operation for reduced temperatures;) thirdly, one burner in one chamber heats one iron, (partial operation for maximum temperatures;) fourthly, one burner in one chamber heats two irons, (partial operation for reduced temperatures,) and so on. The divisibility of the heating-chamber in the manner indicated is the more important and advantageous the more burners such a heater is provided with, and this constitutes a very weighty argument on behalf of economical operation and practical utility. The novel technical effect resides in the feature that by means of the burners according to choice a desired number of irons can be heated simultaneously or successively to different temperatures.

Of special importance for heaters containing many compartments is the arrangement of the hinged door h above referred to. When the said door is open, all the irons are in view and the desired iron can be selected.

Beneath the plate c are provided two rails or guides x and x' , on or between which the removable handles f' of the irons f may be suspended while the irons are being heated.

On or at the rear of the multichamber-heater a controller-board n may be provided, at the rear side of which are led the burner-supply pipes o and the ignition or pilot flame-supply pipes p . The burner-supply pipes o branch off from the main gas-feed pipe q , while the ignition or pilot flame-supply pipes p branch from an auxiliary pipe s , fed by the gas-pipe q , or said pipes p may also branch directly from the said gas-feed pipe q . This latter modification is not shown in the drawings. On the front side of said switchboard n are handles t and u , mounted on the stems of the cocks v and w , said stems passing through the switchboard from the burner-pipes o and the ignition-pipes p , respectively. The stems of cocks v may, as shown, also be provided with arms t' , which may be locked by means of padlocks t^2 or the like to lugs t^2 of the switchboard. The arrangement of the cocks is such that the handles are readily distinguishable and indications may be marked on the handles or on the switchboard to prevent confusion.

When the partition walls h are removed from the heater by means of supports 1, removably mounted in side plates or angles 1^a , the upper part of the heater and of a plate 2, adapted to rest upon the same and provided with perforations 3, a further heating-compartment may be provided in which irons may be placed and so kept warm.

Having thus described my invention, what I claim as new therein, and desire to secure by Letters Patent, is—

1. In a heater for tailors' irons, the combination with a heater-casing, of removable partitions dividing the casing into a plurality of chambers, a burner to heat each chamber and means in each chamber to support an iron.

2. In a heater for tailors' irons, the combination with a frame having a plate for the support of irons and a heater-casing supported by the frame, of vertical partitions supported by the casing and dividing it into a number of chambers, a burner and an iron-support in each chamber, and a door hinged to the casing whose lower edge rests on said plate.

3. In a heater for tailors' irons, the combination with a frame having a plate for the support of irons and a heater-casing supported by the frame, of removable vertical partitions dividing the casing into chambers, a burner and a removable iron-support in each chamber, and a door taking over the front edges of the partitions and whose lower edge rests on said plate.

4. In a heater for tailors' irons, the combination with a frame and a casing supported thereby and provided with means adapted to support vertical partitions and also with means adapted to support a horizontal partition when the vertical partitions are removed, of a main burner, a pilot-flame burner and a removable grid to support the irons and mounted in said casing, and a door hinged to the casing adapted to take over the edges of the partitions.

5. In a heater for tailors' irons, the combination with a frame and a casing supported thereby, of removable partitions to divide the casing into chambers, a burner and an iron-supporting grid in each chamber, said plate located outside the casing to support irons.

6. In a heater for tailors' irons, the combination with a frame having a plate c for the support of irons, and a casing supported by the frame, of removable partitions to divide the casing into chambers, a burner and a removable grid in each chamber, said plate c on a level with the grids.

7. In a heater for tailors' irons, the combination with a frame and a casing supported thereby, of removable partitions to divide the casing into chambers, a burner and a removable grid in each chamber, two deflectors below each grid and a plate c^2 spaced from said deflectors.

EMIL HUGO HENNIGER.
